UNITED STATES PATENT OFFICE.

RUDOLPH C. LUKENS, OF ACADEMY, PENNSYLVANIA.

DESIGN FOR A RAILROAD-TIE.

SPECIFICATION forming part of Design No. 34,764, dated July 9, 1901.

Application filed May 9, 1901. Serial No. 59,537. Term of patent 14 years.

To all whom it may concern:

Be it known that I, RUDOLPH C. LUKENS, a citizen of the United States, residing at Academy, in the county of Montgomery and State 5 of Pennsylvania, have invented and produced a new and original Design for a Railroad-Tie, of which the following is a specification.

This invention relates to a new and original design for a railroad-tie; and the essential features of the same reside in the tie as illustrated in the accompanying drawings, wherein—

Figure 1 is a perspective view of a tie embodying the features of the design. Fig. 2 is 15 a similar view of the tie inverted.

The design is characterized by a body 1, having a rectangular marginal contour. On the upper side of the body near opposite ends of the latter are upstanding diagonally-disposed projections 2, having their inner opposing edges 3 reversely inclined to form dove-

tail recesses 4, which have the same diagonal direction as the projections. On the lower side of the said body is a depending spirally-curved flange 5, extending from one end 25 thereof to the other and alternately running over the body from one side edge to the other, said flange being of equal thickness throughout its length and disposed in a plane at a right angle to the body. 30

Having thus described the invention, what is claimed as new is—

The design for a railroad-tie, as herein shown and described.

In testimony that I claim the foregoing as 35 my own I have hereto affixed my signature in the presence of two witnesses.

RUDOLPH C. LUKENS.
